(57) **CLAIM**

The ornamental design for a cover for a suction cup, as shown and described.

DESCRIPTION

FIG. 1 is a perspective view of cover for a suction cup showing my new design.

FIG. 2 is a front view thereof.

FIG. 3 is a rear view thereof.

FIG. 4 is a right view thereof.

FIG. 5 is a left view thereof.

FIG. 6 is a top view thereof.

FIG. 7 is a bottom view thereof; and,

FIG. 8 is a perspective view showing the cover for a suction cup in a position of use.

The broken lines in the drawing depict environmental subject matter only and form no part of the claimed design.
